Primary Examiner—Mitchell Siegel

[73] Assignee: **Carrier Corporation**, Syracuse, N.Y.

[57] CLAIM

[**] Term: 14 Years

[21] Appl. No.: 29/107,426

DESCRIPTION

[22] Filed: Jul. 6, 1999

FIG. 1 is a perspective view of a louver pattern for a gas furnace door showing our new design;

[51] LOC (7) Cl. 23-99

FIG. 2 is a front elevational view thereof; and,

[52] U.S. Cl. D23/387

FIG. 3 is an enlarged fragmented view taken on line 3—3 of FIG. 2.

[58] Field of Search D23/387, 388,
D23/392, 354; 52/385, 391, 392; 210/163,
460

The broken line showing of a gas furnace door is for illustrative purposes only and forms no part of the claimed design.
